UNITED STATES PATENT OFFICE.

KASSON FRAZER, OF SYRACUSE, NEW YORK.

IMPROVED TRACE-BUCKLE.

Specification forming part of Letters Patent No. **88,952**, dated April 13, 1869.

To all whom it may concern:

Be it known that I, KASSON FRAZER, of Syracuse, in the county of Onondaga and State of New York, have invented a new and useful Improvement in Trace-Buckles; and I do hereby declare the following to be a full, clear, and exact description of the same, sufficient to enable others skilled in the art to which my invention appertains to make and use the same, reference being had to the accompanying drawings, forming part of this specification, and in which—

Figure 1 is a longitudinal central section of my improved buckle; Fig. 2, a top view of the same. Fig. 3 is a top view of the slide detached, with the tongue and spring.

Similar letters of reference indicate corresponding parts in the several figures.

My invention consists in forming the frame of a buckle with inclined sides, on which moves a slide carrying the tongue and spring.

It also consists in placing a flat spring over the tongue of the buckle, whereby said tongue is held firmly in position in the strap, all as hereinafter more fully described.

In the drawings, A is the buckle-frame. This frame may be constructed of brass or other suitable material, and is provided with loops *a a b*, to which the various parts of the harness are fastened. Another loop, *d*, is provided for the connection of the hames-tug B. The upper portion of the frame A forms a cap, C, having a recess, *e*. The sides of the frame are made with inclined surfaces *f f' f'*, for a purpose to be hereinafter explained.

D represents a sliding plate formed with four projections, *i i*, two on each side, at each end of the slide. These projections have beveled surfaces underneath, which rest on the inclined surfaces *f f' f'*, and slide up and down thereon, toward and from the top C of the buckle, holding the strap between said top and the slide. The slide D is provided with a longitudinal slot *g*, through which a tongue, E, plays. The tongue has a shank, *h*, and journals *l l*, which fit in recesses *m*, formed in the slide. The tongue E is held in position by means of a flat spring, F, the end of which presses upon the journals *l l* of said tongue. In order that the spring itself may be held in position, one end is placed under two projections, *r r*, on the slide D.

When it is desired to fasten the trace G, it is placed between the cap C and the slide D,

and then shoved along until the tongue E reaches one of the holes *y y*, into which it is pressed by the action of the spring F, and there securely held. The tongue E passes through the hole *y* into an open recess, *e*, in the cap C.

When the draft of the horse is brought to bear on the traces, the slide rises upon the inclines *f f' f'* and clamps the strap between the slide and the top C, thus rendering the fastening more secure as the draft increases. To release the trace from the buckle, the tongue is withdrawn from the hole which it occupied in the strap, when the latter can be readily drawn out.

These buckles may be made highly ornamental, and, being simple, convenient, and durable, their advantages will be readily seen and appreciated.

Having thus described my invention, what I claim as new, and desire to secure by Letters Patent, is—

1. The frame A, formed with inclined surfaces *f f' f'*, and adapted to receive the slide D, having projections *i i*, all operating substantially as herein described.

2. The tongue E, made substantially as herein set forth, hung in the slide D and pressed down by the flat spring F, substantially as set forth.

3. The frame A, with loops *a a b d*, top C, with recess *e*, and inclined sides *f f' f'*, adapted to receive a slide, D, having projections *i i* and carrying the tongue E, substantially as specified.

4. The slide D, having projections *i i* and provided with a tongue, E, and the spring F, when fitted in a frame, A, having inclined surfaces *f f'*, substantially as set forth.

5. A trace-buckle composed of a slide, D, carrying a tongue, E, and a spring, F, and a frame, A, the slide D moving in the frame on inclined surfaces *i i*, substantially as herein described.

6. The mode of locking and unlocking the tongue by means of two sets of inclined guides, which support both ends of the tongue-slide in the operation of locking and unlocking, substantially as described.

To the above I have signed my name this 6th day of March, 1869.

KASSON FRAZER.
